INVENTOR.

John Smith.

BY

Oscar Geier

HIS ATTORNEY

UNITED STATES PATENT OFFICE.

JOHN SMITH, OF SOUTHBRIIDGE, MASSACHUSETTS.

RAILWAY-TRACK SIGNAL DEVICE.

Specification of Letters Patent. Patented June 24, 1919.

1,307,380.

Application filed August 6, 1917. Serial No. 184,593.

To all whom it may concern:

Be it known that I, JOHN SMITH, a subject of the Emperor of Austria, resident of Southbridge, county of Worcester and State 5 of Massachusetts, have invented certain new and useful Improvements in Railway-Track Signal Devices, of which the following is a specification.

This invention relates to improvements in railway track signaling devices, and has as its principal object the provision of means which will cause an audible signal to be automatically operated upon the passage of a train at some distance from the signal box.

15 A further object is to provide means which intensify the sound produced by the signal bell, so that the same may be heard at a greater distance than is common, and finally, to provide such apparatus in forms 20 which may be easily applied to existing track constructions without material change in the same, and which are comprised of few and simple parts.

These and other like objects are attained 25 by the novel construction and combination of parts hereafter described and shown in the accompanying drawings, forming a material part of this disclosure, and in which—

Figure 1 is a perspective view of a railway 30 track indicating the application of the invention.

Fig. 2 is a vertical sectional view taken on line 2—2 of Fig. 4.

Fig. 3 is a top plan view of the signal 35 view of the signal casing.

Fig. 4 is a transverse sectional view taken on line 4—4 of Fig. 3, and

Fig. 5 is a diagrammatic view illustrating 40 the signal, its wiring and manner of operation.

In the drawings, the railway track indicated, comprises running rails 10 and 12, and is shown to cross a highway 11. Adjacent to the crossing is an audible signal 14, electrically connected with a battery in box 15, from which extend wires 16 and 18 to the respective track rails 10 and 12. It is to be understood that at the point of contact with the wheels 20 of a car a current is conducted 45 through the axle 21 of the wheels from one rail to another, thereby forming a circuit inclosing the wire 18, and the battery in box 15, the current generated in said circuit being used to actuate a bell 24, contained 50 within the signal box 14 in a well-known

manner. It will be clear that the contact made by the wheels with the rails may be at any distance from the signal box.

The invention relates particularly to the construction of the signal box 14, which is 60 provided with extending lugs, by which it may be rigidly engaged to any convenient object, as to one of the telegraph poles adjacent to the crossing, as shown in Fig. 3.

Formed in the cover 25 of the signal box 65 is a circular opening 26, covered with a closely meshed metallic netting 28, similar coverings 29 being arranged at the ends of the casing so as to prevent the intrusion of insects or the like which might disarrange 70 the mechanism of the bell, the end openings being preferably oval in shape and having adjacent to them the enlarged open ends of trumpets or amplifying horns 30, the inner ends being brought closely adjacent to the 75 bell so as to gather the sound therefrom.

Within the central opening 26 is another amplifying horn 32, the smaller end of which is directly over the bell 24, so as to receive the sound therefrom, and it will be 80 obvious that the sound produced by the bell will be intensified to a very considerable extent so that the same may be heard at a greater distance from the signal box than if the plain bell alone were used, and it will 85 also be evident that the construction is of an exceedingly simple character which can readily be applied to existing crossings in an inexpensive manner.

Having thus described my invention what 90 I claim as new, and desire to secure by Letters Patent, is—

In a device of the character described, the combination of a casing provided with sound openings in three of its walls and adapted 95 to be secured to a support with a train-operated electric bell disposed therein in approximately its center, closely meshed metal wire nettings covering said openings, and horns disposed with their inner reduced ends 100 in close proximity to said bell and with their flanged outer widened ends adapted to be secured to the inner walls of said casing for intensifying the acoustic signals produced by the bell.

105 In testimony whereof I have affixed my signature.

JOHN SMITH. [L. S.]

In presence of—
WILFRID J. LANOUREUX.
